UNITED STATES PATENT OFFICE

2,340,239

HIGH WATER INDICATOR

Jesse Abraham Waldrop, Atlanta, Ga.

Application January 7, 1943, Serial No. 471,600

1 Claim. (Cl. 200—84)

This invention relates to a high water indicator.

An object of the invention is the provision of a device which is to be located at strategic points on railways, highways or other places where it is desired to give warning of an excessive rise of water; the warning may be in the form of illuminated signals, sirens or other means, such signals continuing to function until the proper authorities arrive.

Another object of the invention is the provision of a device for warning the proper authorities that an excessive rise of water has taken place along a railroad or highway, such warning continuing until the device is manually reset.

A further object of the invention is the provision of a device for giving signals in the dispatcher's office of a railroad, or wherever desired, that water in a predetermined locality has risen a predetermined level, the device being located at points along the road bed where there is danger of flood conditions.

This invention will be best understood from a consideration of the following detailed description in view of the accompanying drawing forming a part of the specification; nevertheless, it is to be understood that the invention is not confined to the disclosure, being susceptible of such changes and modifications as define no material departure from the salient features of the invention as expressed in the appended claim.

In the drawing:

Fig. 1 is the side view of the device, constructed according to the principles of my invention, with one wall of the casing removed.

Fig. 2 is an end view elevation of the device, with an end wall removed.

Fig. 3 is a horizontal section taken along the line 3—3 of Fig. 4.

Fig. 4 is a fragmentary vertical view of a shaft and bearing.

Referring more particularly to the drawing, 10 designates a base portion of a housing, generally designated by the numeral 11, and mounted on the base portion are side walls 12 and 13. A top or closure 14 is hingedly mounted at 15 on the upper edge of the side wall 12, and is adapted to be locked against unauthorized manipulation. This lock (not shown) is adapted to be connected between the upper edge of the side wall 13 and a longitudinal edge 16 of the top 14. The side and end walls are provided with openings 17 to permit water in the neighborhood to enter the housing 11. Each of these openings are covered with

screens 18 in order to prevent insects or debris finding their way to the interior of the housing.

An L-shaped bracket 20 has a base portion 21, which is secured at 22 to the bottom 10 of the housing. The bracket also includes an upright 23, which is located at right angles to the portion 21. A bearing 24 mounted on the top of the vertical portion 23 of the bracket receives a shaft 25 to which is secured the upper end of a rod 26. This rod extends downwardly and is secured to a float 27 of any suitable type. When the float is at its lowermost position it rests upon a rubber bumper 28, which is secured to the inner surface of the base portion 10 of the housing 11. 10 The vertical portion 23 of the bracket 20 is provided with a lateral extension 30, which has a bearing 31 for a shaft 32. It will be noted that this shaft has a flat portion 23, upon which bears a spring 34, received by a slot 35 in the extension 30. This spring is held in place by means of a set screw 36, threaded into an opening in the lateral extension.

A collar 40 is mounted on one end of the shaft 32 and a rod 41 extends through an opening in the collar, and also through the shaft 32 and is rigidly secured therein so that when the rod 41 is rocked the shaft 32 will likewise be rocked. A hook 42 forms a continuation of the rod 41, and is at right angles thereto as shown in Figs. 1 and 2.

A second collar 43 is pinned at 44 to the shaft 32, at one side of the extension 30. The collar 40 is secured by the rod 41 to the shaft at the other side of the said lateral extension.

35 A mercury switch 45 is held in a horizontal position by a U shaped clip 46, which is connected to a block 47 and this block in turn is connected to the adjacent end of the shaft 32 so that when the shaft is rocked the switch will likewise be rocked for moving the mercury from one end of the switch to the other end for closing the circuit. The switch may be of any type. No details of this switch are shown nor are they described, because this type of switch is well known in the art, and depends upon its functioning by the tilting or moving of a glass tube which contains a quantity of mercury so that when the tube is rocked or shifted the mercury will move to one end of the tube, or to a different portion of the tube. The mercury engages both contacts for closing the circuit.

40 Wires 50 and 51 pass through an insulating member 52 in an end wall of the housing, and are connected to the respective wires 53 and 54, and these wires are connected with a source of cur-

rent, such as a battery or a power line. The wire 50 has a contact 56 from the switch 45, while wire 51 has a socket 57, which receives a contact or pin 58, also projecting from the switch 45. The wires 50 and 51, as well as sockets 55 and 57, are covered with insulating material in order to prevent the water which enters the house 11 from short circuiting the wires. The wires 50 and 51 within the housing are of the flexible type since the switch 45 and the contacts 56 and 58 are rocked by the shaft 32.

The operation of my device is as follows:

The housing 11 is placed in a position so that water, when it rises above a predetermined level in a neighborhood will enter the passage 17 in the housing and thus raise the float 27. When the float is raised sufficiently the rod 26 will engage the upper end of the hook 42 and raise the same, thereby rocking the rod 41.

When the rod 41 is rocked the shaft 32 will be rocked, and the flat portion 33 on the shaft, which is normally in a vertical position, will be moved to the horizontal position shown in Fig. 4. When this happens the spring 34 will engage the flat side and prevent the shaft 32 from returning to its normal inoperative position by the weight of the hook 42.

Since the switch 45 is connected to the shaft 32 said switch will be rocked when said shaft is rocked by the raising of the rod 26, and the movement of the hook 42. At this time the mercury in the switch will move to a point where

it will engage both of the contacts 56 and 58, and thus close the circuit to the source of current.

The signal, energized by the current flowing through the wires 53 and 54, will continue to function until someone has arrived at the location where the housing 11 has been placed, and until the operator manually resets the device to an inoperative position. In other words, in this type of device the shaft 32 must be manually returned to its normally inoperative position.

However, there are cases where the device may function automatically when the water recedes, and the float 27 is lowered. The weight of the hook 42 and the rod 41 will cause the shaft 32 to return to its inoperative position.

I claim:

A device of the class described, comprising a housing, a bracket mounted within said housing, a float-rod pivoted on the bracket and provided with a float, a rock shaft mounted on the bracket, a rod projecting laterally from said shaft, a hook extending upwardly from the rod, at right angles thereto, and straddling the float-rod, said hook being engaged by the float-rod when elevated by the float for rocking the shaft, a switch connected to the shaft and rocked thereby for closing a circuit to a warning signal, said housing having openings for admitting liquid thereto, and means on the bracket and engageable with the shaft for retaining said shaft in position after said shaft has been rocked to close the switch.

JESSE ABRAHAM WALDROP.
